United States Patent Office

Des. 211,460
Patented June 18, 1968

211,460

CHAIR

Hans Zufferey, 50 Scheuchzerstrasse,
Zurich, Switzerland

Filed Aug. 16, 1966, Ser. No. 3,483

Claims priority, application Switzerland June 8, 1966

Term of patent 7 years

(Cl. D15—1)

FIG. 1

FIG. 2

FIG. 3

FIGURE 1 is a front perspective view of a chair showing my new design;

FIGURE 2 is a rear perspective view of the chair shown in FIGURE 1;

FIGURE 3 is a top plan view of the chair shown in FIGURE 1;

The design is characterized by the combination, of the chair disclosed, comprised of a single pedestal and a one-piece molded frame member wherein the vertical backrest portion thereof is composed of essentially tubular sections contoured to receive a cushion constructed of multiple cylindrical sections, all as shown.

I claim:

The ornamental design for a chair, substantially as shown and described.
